ELECTRIC VIOLIN BODY

Clarence L. Fender, 221 N. Lincoln, Fullerton, Calif.

Filed Apr. 10, 1959, Ser. No. 55,449

Term of patent 14 years

(Cl. D56—1)

Fig. 1 is a perspective view of an electric violin body embodying my new design;

Fig. 2 is a reduced top plan view;

Fig. 3 is a reduced bottom plan view; and

Fig. 4 is a reduced side elevational view thereof.

The dominant features of the design reside in the portions shown in full lines.

I claim:

The ornamental design for an electric violin body, substantially as shown and described.
